UNITED STATES PATENT OFFICE.

ANTON RAMOCKI, OF NORTH TONAWANDA, NEW YORK, ASSIGNOR OF ONE-THIRD TO
MARCIN GILL, OF NORTH TONAWANDA, NEW YORK.

SWORD-PISTOL.

1,241,552.

Specification of Letters Patent.

Patented Oct. 2, 1917.

Application filed April 7, 1917. Serial No. 160,430.

To all whom it may concern:

Be it known that I, ANTON RAMOCKI, a subject of the Emperor of Austria, residing at North Tonawanda, in the county of 5 Niagara and State of New York, have invented certain new and useful Improvements in Sword-Pistols, of which the following is a specification.

The primary object of the invention is the 10 provision of a sword pistol of the magazine type adapted for rapid fire work, a readily accessible magazine for the cartridges being arranged while a safety mechanism is provided for the structure.

15 A still further object of the device is the provision of a magazine pistol or revolver which is perfect in its operation of successively shifting and exploding the cartridges, the cartridge magazine being readily shiftable for reloading while a safety catch prevents the operation of the pistol when desired.

20 A still further object of the invention is the provision of a sword pistol in which the sword blade or the pistol may be used separately or together, the entire structure being 25 simple in its construction as well as possessing great strength and durability.

In the drawings forming a part of this 30 application and in which like designating characters refer to corresponding parts throughout the several views:—

Figure 1 is a side elevation of the device with the blade broken away and a portion 35 of the hilt covering removed.

Fig. 2 is a top plan view thereof.

Fig. 3 is a front elevation thereof with the blade shown in transverse section.

Fig. 4 is a view similar to Fig. 3 with 40 the magazine open and with parts broken away.

Fig. 5 is an enlarged detail view of the lower portion of the pistol member.

Fig. 6 is a view partially in top elevation and partially in longitudinal section, with the sword guard and the pistol firing mechanism removed and showing a cartridge arranged within the magazine.

Fig. 7 is a side elevation similar to Fig. 1 with the magazine removed and parts broken away.

Fig. 8 is a perspective view of the swinging mount for the cartridge magazine.

Fig. 9 is a perspective view of the automatic detent detached.

Fig. 10 is a perspective view of the safety catch for the trigger, and,

Fig. 11 is a perspective view of the latch bolt detached.

The present firearm broadly consists of a 60 combined sword hilt and gun stock 10 having a curved hand guard 11 at the lower side thereof, a rectangular mounting frame 12 for a cartridge magazine 13 being forwardly attached with respect thereto while a blade 65 14 forwardly projects from said frame in longitudinal alinement with the stock 10 in parallelism beneath a pistol barrel 15 carried by the frame 12.

A hammer 16 is pivoted as at 17 within 70 the slot 18 of the stock 10, the same having a firing point or pin 18 adapted to project inwardly of the frame 12 through a perforation 19 therein for the purpose of exploding a cartridge, such as 20, arranged within the 75 adjacent chamber 21 of the magazine 13. A loop 22 is provided within one of the openings 23 of the skeleton member 24 of the stock 10 through which a bent leaf spring 25 is positioned having one end thereof secured as at 26 to the member 24 while the opposite end of said spring engages within the rear notch 27 of the hammer 16.

The trigger 28 is pivoted as at 29 within a 80 bottom slot 30 of the skeleton member 24 having a shoulder 31 adapted for the reception of a lug 32 upon the bottom of the hammer 16, as best illustrated in Fig. 7 of the drawings. A leaf spring 33 is secured at 85 one end to the forward end of the loop 22 while the other end of the spring 23 is seated within a notch 34 of the trigger 28. From this arrangement it will be understood that with the members positioned as illustrated in Fig. 7, an upward swinging movement 90 imparted to the trigger 28 by the hand of the operator when grasping the stock 10 will retract the hammer 16 to its cocked position by reason of the engagement of the lug 32 of the hammer with the shoulder 31 of the 100 trigger, such movement placing the springs 25 and 33 under tension. The continued upward movement of the trigger 28 after the hammer has assumed its elevated cocked position, trips the shoulder 31 off of the lug 32, the curved rear side 35 affording clearance for the said lug while the springs 25 and 33 return the trigger and hammer respectively, to their normal positions, thereby firing the 105 mechanism, forcibly projecting the pin 18 110

through the frame opening 19 for engaging the cartridge 20.

A safety catch 36 is pivoted as at 37 to the rear lower corner of the frame 12, the same having its free forked end 38 engaged by a spring finger 39 at the lower forward corner of the frame 12 while the said catch is adapted to swing rearwardly through the bottom slot 40 in the hand guard 11 for engaging the heel 41 of the catch 36 within a bottom notch 42 of the trigger 28 when the latter is in its retracted or fixed position free from the hammer 16.

The magazine 13 is cylindrical in form having the chambers 21 thereof arranged in a circle adjacent its periphery while notches 43 are provided around the same at the rear edge thereof presenting successive parallel shoulders 44 adapted for restraining engagement with a detent or stop 45 vertically shiftably mounted within a slot 46 in the top of the frame 12 and through an oblique slot 46' of the rear side 52 thereof and operatively connected by means of a link 47 with the trigger 28 as at 48. It will be understood that when the finger engaging portion of the trigger 28 is held inoperative by the safety catch 36, as illustrated by dotted lines in Fig. 1 of the drawings, such position takes place after the firing of the cartridge 20 which is positioned forwardly of the pin 18 so that while the trigger 28 is in such safety position, it entirely releases the hammer 16 thereby rendering it capable of manual retraction by engaging the upper end 50' thereof. Any movement of the pin 18 incident thereto could only engage the exploded cartridge 20, as a succeeding cartridge is not brought into firing position until the catch 36 has been released and the trigger 28 again operated. The magazine 13 is adapted to be revolved for successively presenting the chambers 21 in alignment between the firing pin 18 and the barrel 15, the mechanism consisting of a pusher or rod 49 pivoted as at 50 to the trigger 28 and adapted to move through a substantially central slot 51 in the rear side 52 of the frame 12 for engaging the circular arrangement of teeth 53 centrally arranged upon the rear portion of the magazine 13. The said side 52 is in the form of a tapered disk and forms a pommel for the sword and to which the guard 11 is secured as at 52', the opposite end of the guard being attached as at 53' to the free end of the hilt 10. From this arrangement it will be seen that at the time the trigger 28 is elevated, the detent 45 is depressed into engagement with one of the shoulders 44 of the magazine 13, thereby insuring the accurate position of one of the cartridges 20 for firing engagement by the pin 18 while the pusher 49 operates simultaneously with the detent 45 to revolve the magazine 13 for such

proper positioning of the chambers 21 successively in their accurate firing positions. Side coverings 54 preferably of roughened material are provided for the skeleton 24 completing the stock or handle formation and whereby, as will be evident, the operator may grasp the same for using the blade 14 as well as for operating the trigger 28 in firing the pistol.

The magazine 13 has a central hub 55 by means of which the magazine is revolvably journaled upon an axle 56 of the mount 57, the latter being hinged to the lower front corner of the frame 12 at 58. A latch bolt 59 is longitudinally slidably positioned within a chamber 60 in the rear end of the blade 14, a cover plate 61 being provided for the said chamber while a projecting spring 62 is arranged for projecting the bolt 59 rearwardly within the said chamber 60. A pin 63 is carried by the bolt 59 projecting through a side slot 64 in the cover plate 61 whereby the bolt may be retracted when desired, it being noted that a keeper slot 65 is laterally arranged through the blade 14 adjacent the forward side 66 of the frame 12 adapted to receive the arm 67 of the mount 57 and position a notch 68 of the said arm within the locking path of movement of the bolt 59.

The bolt 59 normally engages the arm 67 for retaining the magazine 13 in its closed operative position while upon retracting the bolt 59 by means of the pin 63, the arm 67 is released, permitting the mount 57 and magazine 13 to be swung laterally upon the hinge 58 to its open position, as illustrated in Fig. 4 of the drawing, for permitting the exploded shells to be readily withdrawn from the chambers 21 and the reloading of the chambers. The mount 57 and magazine are readily closed by swinging the same inwardly of the frame 12, the forward inclined face 69 of the arm 67 retracting the bolt 59 for allowing the latter to automatically seat within the notch 68. It will be understood that when the safety catch 36 is in engagement with the trigger 28, the pusher 49 will prevent the opening of the magazine 13 by restraining the lateral swinging movement thereof. A take-up spring 70 is arranged upon the bottom 71 of the frame 12 for frictionally engaging the periphery of the magazine 13 taking up any lost motion which may be present therein, the normal positioning of the magazine serving to slightly tension the said spring 70. A serviceable pistol sword is arranged which may be readily operated for firing as a pistol as well as for use as a sword, the operation of the hammer and trigger mechanism being simple in construction and positive in operation in connection with the accurately positioned cartridge magazine simultaneously automatically operated thereby.

What I claim as new is:—

1. A pistol sword comprising a skeleton hilt frame, a cartridge magazine frame forwardly secured thereto, a coöperating trigger and hammer pivoted in the said skeleton frame, a loop within said skeleton frame, an operating spring projecting through said loop secured at one end to the skeleton frame with its opposite end in engagement with 5 said hammer, and a leaf spring carried by 10 the free end of said loop in operative engagement with the said trigger.
2. A pistol sword comprising a skeleton hilt frame, a cartridge magazine frame forwardly secured thereto, a coöperating trigger and hammer pivoted in the said skeleton frame, a loop within said skeleton frame, an operating spring projecting through said loop secured at one end to the 15 skeleton frame with its opposite end in engagement with said hammer, a leaf spring carried by the free end of said loop in operative engagement with the said trigger, the rear side of the magazine frame having 20 central and upwardly positioned openings therethrough, a firing pin upon said hammer adapted for projection through said upper opening, a cartridge magazine revolvably mounted within said magazine chamber, and a pusher rod for said magazine pivoted to the trigger operatively arranged 25 through the said central opening.
3. A pistol sword comprising a skeleton hilt frame, a cartridge magazine frame forwardly secured thereto, a coöperating trigger and hammer pivoted in the said skeleton frame, a loop within said skeleton frame, an operating spring projecting through said loop secured at one end to the skeleton 30 frame with its opposite end in engagement with said hammer, a leaf spring carried by the free end of said loop in operative engagement with the said trigger, a forwardly projecting blade carried by said magazine frame, a retractable spring-pressed bolt carried by said blade, and a laterally swinging mount for said magazine hinged to said magazine frame and provided with a keeper notch within the path of movement of said bolt.
4. A pistol sword comprising a skeleton hilt frame, a cartridge magazine frame forwardly secured thereto, a coöperating trigger and hammer pivoted in the said skeleton frame, a loop within said skeleton frame, an operating spring projecting through said loop secured at one end to the skeleton frame with its opposite end in engagement with said hammer, a leaf spring carried by the free end of said loop in operative engagement with the said trigger, the rear side of the magazine frame having central and upwardly positioned openings therethrough, a firing pin upon said ham- 50
- mer adapted for projection through said upper opening, a cartridge magazine revolvably mounted within said magazine frame, a pusher rod for said magazine pivoted to the trigger operatively arranged through the said central opening, a forwardly projecting blade carried by said magazine frame, a retractable spring-pressed bolt carried by said blade, and a laterally swinging mount for said magazine hinged to said magazine frame and provided with a keeper notch within the path of movement of said bolt.
5. A pistol sword comprising a hilt and blade arranged in substantial longitudinal alinement, a rectangular frame connecting said hilt and blade, a laterally swinging mount hinged to the said frame, a cartridge magazine revolvably journaled upon the said mount adapted for positioning inwardly of the frame, and a pistol barrel forwardly projecting from said frame adjacent the said blade.
6. A pistol sword comprising a hilt and blade arranged in substantial longitudinal alinement, a rectangular frame connecting said hilt and blade, a laterally swinging mount hinged to the said frame, a cartridge magazine revolvably journaled upon the said mount adapted for positioning inwardly of the frame, a pistol barrel forwardly projecting from said frame adjacent the said blade, a retaining latch for said mount carried by said blade, and firing mechanism associated with the said frame carried by the hilt.
7. A pistol sword comprising a hilt and blade arranged in substantial longitudinal alinement, a rectangular frame connecting said hilt and blade, a laterally swinging mount hinged to the said frame, a cartridge magazine revolvably journaled upon the said mount adapted for positioning inwardly of the frame, a pistol barrel forwardly projecting from said frame adjacent the said blade, the said blade having a longitudinal chamber therein, and a transverse slot communicating with said chamber, a retractable spring-pressed bolt within said chamber normally projected within said slot, an arm carried by the said mount having a keeper notch therein adapted for automatic engagement by the said bolt during the inward swinging closing movement of the magazine.
8. A pistol sword comprising a hilt, a cartridge magazine frame carried by the hilt, pistol mechanism including a trigger having a receiving notch carried by said hilt, a hand guard carried by the frame and hilt provided with a slot in the lower portion thereof, a safety catch hinged to said frame having a path of movement through the said slot adapted for engaging within 120
- 125

the said notch when the trigger is in its elevated inoperative position after the firing operation.

9. A pistol sword comprising a hilt, a cartridge magazine frame carried by the hilt, pistol mechanism including a trigger having a receiving notch carried by said hilt, a hand guard carried by the frame and hilt provided with a slot in the lower portion thereof, a safety catch hinged to said frame having a path of movement through the said slot adapted for engaging within

the said notch when the trigger is in its elevated inoperative position after the firing operation, the said safety catch having a 15 forked free end, a projecting spring carried by said frame adapted for engaging the forked end of said catch when the latter is in its inoperative position, a cartridge magazine within said frame operatively associated with the said trigger, and a barrel 20 forwardly carried by said frame.

In testimony whereof I affix my signature.
ANTON RAMOCKI.
